PELOPIDAS TSUKALAS, OF ATHENS, GREECE.

SIGHTING DEVICE FOR GUNS.

1,033,494.

Specification of Letters Patent.

Patented July 23, 1912.

Application filed October 5, 1911. Serial No. 653,062.

To all whom it may concern:

Be it known that I, PELOPIDAS TSUKALAS, a subject of the King of Greece, residing at Athens, in the Kingdom of Greece, have invented new and useful Improvements in Sighting Devices for Guns, of which the following is a specification.

The present invention relates to sighting devices for guns, used in firing against targets of varying distance; and the object of the invention is to provide sights of this character which automatically adapt themselves to the change of the target distance. This object is attained according to this invention, by inserting between that part of the sighting device that serves for setting the firing angle to correspond to the distance and the guide for said part, a change gear that can be driven by a motor of practically uniform speed (a clockwork for instance), the ratio of transmission of which change gear is so adjusted by hand to correspond with the speed of the target referred to upon the direction of fire, that the part serving to adjust the firing angle is automatically adjusted an amount corresponding to the change of target distance when the change gear is being driven by the motor.

One illustrative embodiment of the invention is shown in the accompanying drawing, in which:—

Figure 1 is a rear view, partly in section, of an attachment sighting device together with parts of the gun that have to be considered in connection therewith; Fig. 2, a side view of Fig. 1, seen from the left, and, Fig. 3, a section of Fig. 1 on line 3—3, seen from the right.

The gun barrel A is in the usual manner carried in a cradle B, on which a bracket C is firmly attached, near the breech end of the gun. Upon this arm is arranged a guide c^1 constituting the attachment housing for the arcuately curved attachment bar E which carries a telescope D. By means of a hand wheel f^1 and a pinion F, both carried by the attachment housing c^1 and rack teeth c^2 on the attachment bar E with which said pinion meshes, the latter may be adjusted by hand to the elevation that corresponds to the ascertained distance. The tooth gear F need have no automatic catch. A clamp screw R carried by the attachment housing

c^1 , is provided for clamping the attachment bar. A range scale e^2 (Fig. 1) on the bar E and an index mark e^2 on the sleeve guide c^1 enables the reading of the range.

For automatic setting of the sight for targets with varying range, a cam gear has been provided driven by a motor (as for instance a clockwork) of which the following is a description.

A drum G, with a cam surface g^1 , is seated on a shaft H, at right angles to the gun axis; said shaft H being mounted to turn in its bearings in the sleeve housing c^1 and the arm c^2 . A motor (a clockwork for instance) is inclosed in a casing c^4 on the arm c^3 adapted to drive the drum in the direction of the arrow w , Figs. 2 and 3, with a comparatively small, uniform angular speed. A suitable speed is for instance one turn of the shaft in twelve minutes. To transmit the turning movement of the shaft H to the drum G, which latter runs loose on the shaft, a claw-coupling is provided, of which one half h^1 is firmly connected with the shaft H, and the other half formed by the hub g^2 of the drum. A spring J, Fig. 1, is pushing the two halves of the coupling together.

Only that part of the cam surface g^1 that lies on the outer side of the angular space $u y z$, Fig. 3, is utilized for automatically setting the sight for a target of varying distance. Said part of the cam surface has been given such a shape that a section taken in the middle of the drum G and perpendicular to its revolving axis will cut it along the circle line g^3 , Fig. 3, the center of which is situated in the revolving axis of the drum; while all the other parallel sections of the drum are inclosed by Archimedean spirals g^6 . Said spirals on the one side of the middle section of the drum inclosed by circle g^3 , converge toward the revolving axis of the drum; they on the other side of said middle section diverge from the same axis.

All of the curves g^5 , g^6 , start from a line parallel with the revolving axis of the drum in a plane $y u$ situated in the unused part of the angular space inclosing the cam surface g^1 , the projection of said line being a point g^4 in Fig. 3. The curves are all brought back in straight lines to their start-

ing points on the inner side of the angular space $u y z$.

The member adapted to coöperate with the drum G in the said cam gear consists 5 of an arm P, resting with its spherical head p^1 , situated at its free end, on the cam surface g^1 . At its other end this arm is carried to slide parallel with the axis of the drum, in a sidewise projecting sleeve k^1 of a slide 10 K, which loosely incloses the sight rack E and may be clamped thereto by a thumb-screw M. By means of an adjusting screw N mounted in the sleeve k^1 , the arm P may be so adjusted that it can coöperate with 15 any one of the curves of the cam surface g^1 . The head p^1 of the arm P is constantly drawn down against the cam face g^1 of the drum G by means of two helical springs Q, Fig. 4.

20 When the slide K is clamped to the bar E by the clamp screw M, and the arm P is so adjusted through the adjusting screw N, that it can coöperate with one of the spirals g^6 , the sight rack E must, through 25 the turning of the drum G, move up or down with a practically uniform speed in consequence of the properties of the Archimedie spiral, according as the arm P moves closer to, or away from the axis of the drum 30 G, the tangent point of the arm P following one of the spirals as the drum turns.

By the choice of suitable constants for the spirals g^6 and by adjusting the arm P, it is easy to obtain a movement of the sight 35 bar adapted to the speed with which the range changes, *i. e.* the speed of the target referred to the direction of fire. In other words, the sight bar is so set that when the speed of the target is constant, its position 40 at every moment corresponds to the target distance. When the arm P is so adjusted that its spherical head p^1 rests on the circular line g^3 of the cam surface g^1 , no change in the position of the sight bar E 45 will take place by the rotation of the drum G. This position of arm P expresses that particular case, when the target distance is constant.

In the following description of the manner in which this device is to be operated, 50 we will suppose that the distance of the target is measured on a range finder at certain intervals. After the first observation, the setting is done by hand for a height corresponding with the observed target distance. The thumb screws M and R are for 55 this purpose first loosened. Then the sight bar, which is now free to run in the housing c^1 and the slide K, is elevated by turning 60 the hand wheel f^1 , until the index c^2 points to the line on the scale e^2 which corresponds to the observed range. Now, in order to have the sight bar move automatically with the varying range, one proceeds as follows. 65 The thumb screw M is first tightened so

that the slide K is firmly connected with the sight bar E. The motor, coupled to the drum G, is then started, driving the drum with uniform speed in the direction of the arrow α , Figs. 2 and 3. The arm P is at the same time set over any desired curve of the drum G. The turning of the drum G is transferred to the sight bar E, through the cam drive $g^1 P$, in such a manner that the sight bar is elevated or depressed an amount corresponding with the movement of the arm P. The pinion F is simultaneously turned by the teeth e^1 and partakes of the movement of the rack without interfering with the automatic setting of the sight rack. 70 After the second reading of the range on the range-finder, the new found range does as a rule not agree with the one indicated on the scale e^2 by the index c^2 . 75 In that case, it will be enough to shift the arm P, along one of the meridians of the cam surface g^1 by turning the adjusting screw N, until the sight rack E, which hereby runs in the housing c^1 , has arrived at such a position that the reading of index c^2 on scale e^2 is the same as the range given 80 by the range-finder. The arm P now stands over that curve which expresses the target speed during the period that lies between the two range observations. Should now the 85 target speed remain uniform the third and each following reading on the range-finder will agree with the range indicated on scale e^2 by the index c^2 . As, however, the range 90 seldom changes regularly, the third observation of the range finder will show a small difference between itself and the reading on scale e^2 . This difference will be still further diminished by turning the adjusting screw in the above-described manner. After 95 each following range observation, the same 100 operation is repeated. Should the drum G from continuous turning have arrived at such a position that the spherical head p^1 of the arm P touches the drum near the idle 105 part of the cam surface g^1 that is limited by the legs of the angle $u y z$, the thumb screw M has to be loosened and the sight 110 rack E clamped by tightening thumb screw R. Thereupon the coupling $h^1 g^1$ is released 115 and the drum G revolved so far in the direction of the arrow α around the shaft H, that the spherical head again touches the operating part of the cam face. After the 120 coupling between the drum G and the shaft H has again been put in action, and the thumb screw M tightened, the thumb screw R is loosened and the sight bar E will again be automatically elevated with the same speed as before. 125

It will be evident from the above description that the sighting device forming the subject of this invention is suitable for firing against a moving target (from a stationary or moving gun mount); but may 130

be equally well applied for firing at stationary targets from a movable gun mount (as for instance on board ship).

I claim:—

5. 1. In a gun sighting device for guns for firing at targets with varying range, the combination with a member used for setting the sight at a firing angle corresponding to the range, and a guide for said member; of 60
10 a change gear having a revolving cam drum inserted between said member and said guide, and a motor for driving the gear at a uniform speed.
2. In a gun sighting device for guns for 15 firing at targets with varying range, the combination with a member used for setting the sight at a firing angle corresponding to the range, and a guide for said member; of a change gear having a revolving cam drum 65
20 inserted between said member and said guide, and a motor for driving the gear at a uniform speed, said gear when driven by the motor and after having been regulated by hand for a ratio of transmission depending 70
25 on the speed of the target as regards the firing direction, being adapted to automatically operate said member to follow the change of the range.
3. In a sighting device for guns for firing 30 at targets with varying range, the combination with a bar used for setting the sight at a firing angle corresponding to the range and a guide for said bar; of a slide on said bar adapted to be firmly secured thereon, 35 a cam drive, comprising a drum revolvably mounted in bearings on said guide and an arm resting with its free end on the cam surface of said drum, and its other end slidably mounted in said slide in a direction 40 parallel with the axis of the drum.
4. In a gun sighting device, the combination with a sight elevating bar and a guide for said bar; of a slide on the bar, a clamping device between the slide and the bar; a 45 cam drive for said elevating bar and a motor operating said cam drive for the purpose of automatically varying the sight elevation in accordance with the variation in range, said cam drive comprising a revolving drum mounted on said guide, an arm 50 resting with its free end on the cam surface of the drum, and its other end mounted in said slide and an adjusting screw for regulating by hand in the direction of the axis 55 of the drum, the position of said arm relative to the drum.
5. In a gun sighting device, the combination with a sight elevating bar and a guide for said bar; of a slide on the bar, a clamping device between the slide and the bar; a cam drive for said elevating bar and a motor operating said cam drive for the purpose of automatically varying the sight elevation in accordance with the variation in range, said cam drive comprising a revolving drum mounted on said guide, an arm resting with its free end on the cam surface of the drum, and its other end mounted in said slide and an adjusting screw for regulating by hand in the direction of the axis 60 of the drum the position of said arm relative to the drum, the middle cross section of said drum having a circular outline, concentric with the drum axis, the other parallel cross sections all having outlines formed by 65 increasing Archimedean spirals on one side of the middle section and decreasing ones on the other.
6. In a gun sighting device, the combination with a sight elevating bar and a guide 70 for said bar; of a slide on the bar; a clamping device between the slide and the bar; a cam drive for said elevating bar and a motor operating said cam drive for the purpose of automatically varying the sight elevation in accordance with the variation in 75 range, and a releasable clutch, normally in engagement, between said motor and said cam drive.
7. In a gun sighting device for guns firing 80 at targets with varying range, the combination with a member used for setting the sight at a firing angle corresponding to the range; of a motor running with uniform speed for driving said member; a change 85 gear inserted between the motor and said member, said change gear comprising a revolving drum and an arm resting with its free end on the cam surface of said drum; and means for displacing the arm and the 90 drum relatively to each other in the direction of the axis of said revolving drum, whereby to adjust said change gear for a ratio of transmission depending on the 95 speed of the target as regards the firing direction.

In testimony whereof I have affixed my signature in presence of two witnesses.
